UNITED STATES PATENT OFFICE.

ALGENON SEADON SPAULDING, OF WORCESTER, MASSACHUSETTS.

CUTTER-HEAD.

SPECIFICATION forming part of Letters Patent No. 531,396, dated December 25, 1894.

Application filed February 25, 1892. Serial No. 422,786. (No model.)

To all whom it may concern:

Be it known that I, ALGENON SEADON SPAULDING, of Worcester, in the county of Worcester and State of Massachusetts, have 5 invented a certain new and useful Improvement in Cutter-Heads, of which the following is a specification, reference being had to the accompanying drawings, forming a part of the same, and in which—

10 Figure 1 represents a cutter-head with the knives and break-irons attached thereto. Fig. 2 is an end view of the break-iron, and Fig. 3 is a view of that side of the break-iron lying next the cutter-head.

15 Similar letters refer to similar parts in the different figures.

My invention relates to the plate known as the break-iron which is interposed between the cutting knife and the side of the cutter-head as hereinafter described and specifically set forth in the annexed claims.

Referring to the accompanying drawings, A denotes the cutter-head of the usual form and provided with the T-shaped grooves A' 25 to receive the heads of the attaching bolts A² by which the cutting knives are held in position in the usual and well known manner.

B, B, are the knives secured upon opposite sides of the cutter-head A by bolts A² 30 and nuts A³. Between the knives B, B, and the sides of the cutter-head A are interposed the break-irons C, C, provided with elongated holes C', through which the attaching bolts A² pass. One edge of the break-iron C overhangs the side of the cutter-head A and is 35 provided with a convex rib or bead C² forming a shoulder C³ which bears against the corner of the cutter-head. At each end of the break-iron a T-shaped piece of metal is 40 moved forming the opening C⁴ and leaving the projecting wings C⁵ as indicated by the broken lines in Fig. 3. When the break-iron is applied to the side of the cutter-head the wings C⁵, which hitherto lay in the plane of 45 the break-iron are bent and turned into the T-groove A' as represented at C⁶, drawing the shoulder C³ firmly against the corner of the cutter-head.

The T-shaped opening C⁴ is made large 50 enough to allow for the variation in different cutter-heads of the distance between the corner of the cutter-head and the T-shaped slot A', allowing the break-iron to be fitted to the cutter-head to which it is to be applied 55 so as to draw the shoulder C³ against the side

of the cutter-head. The outer surface of the break-iron to which the knife is to be applied, is slightly curved at the overhanging edge 60 slightly raising the tip a, as shown in Fig. 2, so that when the knife is applied the under surface of the knife will be drawn firmly against the tip a by the attaching bolts, which forms a tight joint preventing the admission of shavings between the break-iron and the cutting-knife. As the shaving is raised by 65 the cutting edge b, it strikes against the convex surface C², causing it to be deflected and broken, thereby preventing the splitting of the fibers of the wood, in advance of the action of the knife and the force exerted 70 against the convex surface C² will be received by the shoulder C³ bearing against the corner of the cutter-head. Unless the break-iron is securely locked in position by means of the abutting shoulder C³, it is difficult 75 to hold the knives and break-irons from displacement when the machine is in operation, especially in hard or knotty wood. The wings C⁵ are preferably formed at the ends of the break-iron, but it will be obvious that projecting wings adapted to be bent into the T-shaped grooves A' could be formed in the central section of the break-iron if desired. 80

What I claim as my invention, and desire 85 to secure by Letters Patent, is—

1. The combination with a cutter-head and cutting knife attached thereto, of a break-iron interposed between said knife and cutter-head and provided with an abutting shoulder C³ bearing against the side of the cutter-head, 90 substantially as described.

2. The combination with a cutter-head provided with grooves and cutting knife attached thereto, of a break-iron interposed between said cutter-head and said knife and provided 95 with wings C⁵, which are bent or turned into grooves of said cutter-head, substantially as described.

3. The combination with a cutter-head and cutting knife attached thereto, of a break-iron interposed between said cutter-head and said knife and having its edge next the cutting edge of the knife slightly raised, substantially as described. 100

Dated this 17th day of February, 1892.

ALGENON SEADON SPAULDING.
